TABLE

John I. Norris, High Point, N. C.

Application August 8, 1931, Serial No. 556,013
Renewed September 5, 1933

5. Claims. (Cl. 45—112)

This invention relates generally to tables and more particularly to extension tables and has for its primary object to provide, in a manner as hereinafter set forth, a table of this character embodying novel means for storing extra leaves when said extra leaves are not in use, said means being invisible except when the table is open to remove or replace the extra leaves and comprising a structure through the medium of which the leaves are supported out of contact with each other, thus preventing damage to the highly polished surfaces thereof.

Another important object of the invention is to provide a table of the aforementioned character embodying novel means for storing comparatively small, valuable articles such as silverware, in concealment.

Other objects of the invention are to provide a table of the character described which will be simple in construction, strong, durable, efficient and reliable in use, highly attractive in appearance and which may be manufactured at low cost.

25 All of the foregoing and still further objects and advantages of the invention will become apparent from a study of the following specification, taken in connection with the accompanying drawings wherein like characters of reference 30 designate corresponding parts throughout the several views, and wherein:—

Figure 1 is a view in top plan of the table showing said table extended with the extra leaves disposed in the tray provided for the storage thereof.

35 Figure 2 is a view in vertical longitudinal section taken substantially on the line 2—2 of Figure 1, looking in the direction indicated by the arrows.

Figure 3 is a view in vertical cross section taken substantially on the line 3-3 of Figure 1, looking 40 in the direction indicated by the arrows.

Figure 4 is a view in top plan of the tray with the extra leaves removed therefrom.

Figure 5 is a vertical longitudinal sectional view taken substantially on the line 5—5 of Figure 4, looking in the direction indicated by the arrows. Figure 6 is a view in vertical longitudinal sec-

Figure 6 is a view in vertical longitudinal section taken substantially on the line 6—6 of Figure 4, looking in the direction indicated by the arrows. Figure 7 is a detail view in perspective of one

50 Referring now to the drawings in detail, it will

be seen that the reference numeral 1 designates permanent leaves of the table top which are connected together for movement toward and away from each other by the slidably connected pairs of rails 2, 3 and 4. A frame 5 is secured beneath the marginal portions of the leaves 1 and depending from said leaves 1 are the aprons 6. Cross members 7 extend beneath the end

portions of the table top for supporting said table top on the pedestals or legs 8.

A tray designated generally by the reference numeral 9 is disposed between the rails of the table and said tray includes the side bars 10 which are permanently secured, in any suitable manner, to the inner faces of the rails 2. The tray 9 further includes the end bars 11 extending between the ends of the side bars 10. Extending between the end bars 11 is a pair of spaced, parallel, intermediate bars 12 which divide the tray into a pair of outer leaf receiving compartments and an intermediate article receiving compartment which is designated by the reference numeral 13. A board 14 is secured to the lower edges of the intermediate bars 12 and constitutes the bottom of the compartment 13. The marginal portions of the board 14 are disposed outwardly of the outer faces of the bars 12, as illustrated to advantage in Figure 3 of the drawings. 65 70 75 80

Supporting strips 15 are secured to the lower edges of the side bars 10 of the tray 9 and extend inwardly therefrom beneath the leaf receiving compartments. Strips 16 are disposed longitudinally between the elements 14 and 15 and have their end portions secured to the lower edges of the end bars 11 of the tray 9. Otherwise, the leaf receiving compartments of the tray 9 are open at their bottoms.

and project outwardly thererom for engagement in the sockets provided in the other longitudinal edges of the extra leaves 20. The upper series of pins 21 are offset with respect to the lower series of pins 22, as illustrated to advantage in Figures 4 and 5 of the drawings. The lower pins 22 are in transverse alignment with the notches or recesses 18 in the cleats 17. Thus, when the extra leaves 20 are positioned in the tray 9, the upper and lower leaves will be longitudinally offset relative to each other and the pins 19 on the uppermost leaves will rest on the upper edges of the cleats 17. Certain of the extra leaves 20 are provided with hingedly connected aprons 23 and these leaves are stored uppermost in the tray 9. This is illustrated to advantage in Figure 2 of the drawings. It may be well to here mention that the extra leaves are stored in the tray 9 in inverted position. It will thus be seen that the leaves are supported in the tray 9 in spaced 105 110 115 120

relation to each other and in a manner to permit the same to be expeditiously removed or replaced.

To remove the extra leaves from the tray 9, 5 the table is opened to the position seen in Figure 1 of the drawings and the uppermost leaves are swung upwardly and inwardly away from the cleats 17 until said upper leaves can be disengaged from the pins 21. This operation may then 10 be received on the lowermost leaves. To insert the extra leaves in the tray, the foregoing operation is reversed, the lowermost leaves being manipulated to engage the pins 22 in the sockets in said lowermost leaves after which the same 15 are swung downwardly until the pins 19 thereof rest in the notches or recesses 18 of the cleats 17. The uppermost leaves may then be inserted in substantially the same manner, the upper pins 21 positioning said upper leaves so that the pins 19 20 thereof engage on the upper edges of the cleats 17. The construction and arrangement of the tray 9 is such that, when the table is closed, said tray will be invisible when viewed from either side or end of the table. This constitutes 25 a most important and desirable feature of the invention, as will be readily appreciated. Then, too, the construction and arrangement of the tray is such that one end of each of the leaves stored therein will be spaced from one end of 30 the tray a distance sufficient to permit insertion of a hand therebetween to facilitate removing the leaves.

It is believed that the many advantages of a table constructed in accordance with the present invention will be readily understood, and although the preferred embodiment of the invention is as illustrated and described, it is to be understood that changes in the details of construction and in the combination and arrangement of parts may be resorted to which will fall within the scope of the invention as claimed.

What is claimed is:—

1. An extension table comprising a top including pairs of slidably connected rails and leaves mounted on certain of the rails, and a tray disposed between the rails below the horizontal plane of the leaves for the reception of extra leaves in superposed relation, said tray including a pair of spaced, parallel bars, a cleat secured on one of the bars having notches therein for the reception of pins on one edge of the lowermost extra leaf, and upper and lower series of pins mounted on the other bar for engagement in sockets in the other edges of the extra leaves, the lowermost series of pins being aligned with the notches in the cleat, the uppermost series of the pins being out of alignment with the notches in the cleat, the pins on the uppermost extra leaf being engageable for support on the upper edge of the cleat.

2. An extension table comprising a top including pairs of slidably connected rails and leaves mounted on certain of the rails, and a tray disposed between the rails below the horizontal plane of the leaves for the reception of extra leaves in superposed relation, said tray including side bars fixed to one pair of the rails, intermediate bars disposed in spaced parallelism to the side bars, said intermediate bars dividing the tray into a pair of compartments for the reception of the extra leaves, cleats secured on the inner faces of the side bars having notches there-

in for the reception of pins on one longitudinal edge of the lowermost leaves, and upper and lower series of pins mounted on the intermediate bars and projecting therefrom toward the side bars, the lowermost series of pins being aligned with the notches in the cleats, the uppermost series of pins being out of alignment with the notches in the cleats, said series of pins being engageable in sockets in the other longitudinal edges of the extra leaves, the pins on the uppermost extra leaves being engageable for support on the upper edges of the cleats.

3. An extension table comprising a top including pairs of slidably connected rails and leaves mounted on certain of said rails, and a tray disposed between the rails below the horizontal plane of the leaves for the reception of extra leaves in superposed relation, said tray including side bars fixed to the inner sides of one pair of the rails, end bars extending between the side bars, spaced, parallel intermediate bars extending between the end bars in spaced parallelism with the side bars, said intermediate bars providing outer compartments in the tray for the reception of said extra leaves and an intermediate compartment in the tray for the reception of articles, cleats secured on the lower portions of the inner faces of the side bars having notches therein for the reception of pins on one longitudinal edge of the lowermost extra leaves, and upper and lower series of pins mounted on the outer faces of the intermediate bars and projecting therefrom toward the side bars, said series of pins being engageable in sockets in the other longitudinal edges of the extra leaves, the lowermost series of pins being aligned with the notches in the cleats, the uppermost series of pins being out of alignment with the notches in the cleats, the pins on said one longitudinal edge of the uppermost leaves being engageable on the upper edges of the cleats for support thereby.

4. An extension table comprising a supporting structure, permanent leaves mounted on the supporting structure, a tray for the reception of extra leaves, mounted beneath the permanent leaves, said extra leaves having sockets in one edge and pins on another edge, said tray including spaced bars, a cleat mounted on one of the bars having notches therein for the reception of the pins on the extra leaves, and upper and lower pins projecting from the other bar for engagement in the sockets in the extra leaves, the upper pins being out of vertical alignment with the lower pins.

5. An extension table comprising a supporting structure, permanent leaves mounted on the supporting structure, a tray for the reception of extra leaves, mounted beneath the permanent leaves, said extra leaves having sockets in one edge and pins on another edge, said tray including spaced bars, a cleat mounted on one of the bars having notches therein for the reception of the pins on the extra leaves, and upper and lower pins projecting from the other bar for engagement in the sockets in the extra leaves, the upper pins being out of vertical alignment with the lower pins, said lower pins being longitudinally aligned with the notches, the pins on the extra table leaf which is engaged with the upper pins on said other bar being engageable on the upper edge of the cleat.

JOHN I. NORRIS.
